UNITED STATES PATENT OFFICE.

WILLIAM ARTHUR HONEYMAN, OF SAN FRANCISCO, CALIFORNIA.

DESIGN FOR A DISPLAY-CARD.

56,814.

Specification for Design.

Patented Dec. 28, 1920.

Application filed January 29, 1920. Serial No. 355,978. Term of patent 7 years.

To all whom it may concern:

Be it known that I, WILLIAM ARTHUR HONEYMAN, a citizen of the United States, residing at San Francisco, in the county of San Francisco and State of California, have invented a new, original, and ornamental Design for Display-Cards, of which the following is a specification, reference being had to the accompanying drawing, forming a part thereof.

The figure is an elevation of a display card, embodying my invention, the same including a number of articles of manufacture designed to be attached thereto.

I claim:—

The ornamental design for a display card, as shown.

WILLIAM ARTHUR HONEYMAN.
